UNITED STATES PATENT OFFICE.

PERRY RAPP AND MAX D. RATNER, OF CHICAGO, ILLINOIS.

STITCH MARKER.

Application filed August 8, 1922. Serial No. 580,545.

To all whom it may concern:

Be it known that we, PERRY RAPP and MAX D. RATNER, citizens of the United States of America, and residents of Chicago, county of Cook, and State of Illinois, have invented a new and useful Improvement in Stitch Markers, of which the following is a specification.

This invention relates mainly to the manufacture of clothing and especially to methods and means for stitch marking the fabric to be used.

It has long been customary in the manufacture of clothing to simultaneously mark a number of pieces of cloth laid together. This has usually been accomplished by means of thread sections commonly known as stitch markers. Heretofore the stitch marking process has involved a good deal of hand labor, and each piece of cloth has had to have separate attention in cutting the threads. Hence the process was slow and tedious.

The main objects of this invention are to provide an apparatus of improved form adapted for simultaneous cutting of the marker threads for the several pieces of cloth by a single operation or movement of the hand; to provide a machine adapted to run the thread through the cloth and then hold the lower end securely while loops are being pulled between the several layers of cloth; to provide mechanical means for successively pulling the several loops; to provide in such a machine, cutting blades of suitable form disposed between the several layers to simultaneously cut the threads after the loops have been formed; to set thread cut off sections of predetermined and equal length between the several layers of cloth, paper or other fabric and also at the top and bottom of the "lay;" to provide a machine adapted for design to accommodate a lay of any desired height or number of layers; to provide a positive automatic thread lock to enable the insertion of either double or single thread markers; and to provide positive means for clamping the stitched portion of the lay to the frame when the markers are cut.

An illustrative embodiment of this invention is shown in the accompanying drawings, in which—

Figure 1 is a plan of the machine.
Fig. 2 is mainly a side elevation, part

being in vertical longitudinal section.

Fig. 3 is a view of the underside of the machine.

Fig. 4 is a section on the line 4—4 of Fig. 2.

Fig. 5 is mainly an enlarged fragmentary underside plan of the middle or stitch making part of the machine, part being in horizontal section.

Fig. 6 is a vertical section substantially on the line 6—6 of Fig. 5 with the needle raised in its normal position.

Fig. 7 is similar to Fig. 6 except that the needle is lowered and the thread catch is entering the loop.

Fig. 8 is a vertical section on the line 8—8 of Fig. 3.

Fig. 9 is a broken perspective view of the inner end of a pair of the thread drawing and cutting blades and associated cloth and thread.

Fig. 10 is an enlarged cross section on the line 10—10 of Fig. 1.

In the construction shown in the drawings, the machine comprises a substantially unitary frame 1, which may be of integral character, in combination with two principal mechanisms 2 and 3, the one for inserting the thread to form the stitch marks, and the other for pulling the loops and cutting the thread.

The first mechanism 2 resembles somewhat in general appearance an ordinary sewing machine, but is structurally very different and is much simpler in makeup and operation, as will be described.

The second mechanism or loop pulling and cutting means 3 comprises mainly a series of blades 4 disposed side by side, one above another, in slightly spaced relation, and fastened pivotally at their outer ends to a common vertical axis 5 on a movable support 6, in combination with handle means 7 for swinging the several blades in succession horizontally a predetermined distance to form the thread loops, and handle means 8 on the support 6 for pulling the group of blades simultaneously in their longitudinal outward direction to cut the marker thread 9.

The stitch inserting mechanism 2 comprises mainly an upright post 10 disposed over the bed plate of frame 1 where it is supported by the bracket or arm 11, a downwardly movable foot or clamp member 12

to secure the goods in place, a needle holder 13 and a plurality of thread guides 14, 15, and 16.

The blades 4 may be set simultaneously 5 in their stitch receiving position, as in Fig. 1, by means of the bent lever 17 pivoted at 18 to the head 19 on the carrier strip 6. Said lever has a handle arm 20 disposed over and adjacent to the handle 8 and a side arm 10 21 having a vertical bearing tip 22 to contact against the outer edges of arms 7 for gang restoring control thereof. The handle arms 7 are of different lengths and have a stepped arrangement to facilitate successive 15 manual selection for operation in pulling in the stitch loops 23. The inner ends of the blades 4 and blade-like support 6 are longitudinally slotted at 24 to register with the needle 25. The slots 24 are oblong lengthwise of the blades and are preferably oval in shape with the large end under the needle and the narrow ends extending away from handle 8, the latter ends and adjacent trailing edges being sharp edged as indicated at 20 24' and 24'' on Fig. 9, for severing the threads when the blades are pulled outwardly by handle 8.

An adjustable stop 26 on the head 19 limits the outward swing of the blades. Said 30 stop is secured by set screws 27 disposed in horizontal slots 28 in the shank 26' of said stop. If a shorter loop is desired the stop 26 is moved inward toward the needle accordingly, and vice versa. In order to facilitate assembling and interchanging parts 35 the head 19 is provided with a socket 29 and the blades 4 are assembled directly on a plug member 30 fitting in said socket where held by a set screw 31, as shown by Fig. 10. The 40 projecting end of plug 30 is slotted to receive the angular blade ends and the pivot 5 set in said plug holds the blades in operative position. The screw 31 bears directly against a clamping filler-block 32 as shown 45 in Fig. 10. Head 19 is secured to strip 6 by the plate 33 and screws 34. The top plate 33' is held by screws 34'. The restoration movement of blades 4 is limited by a 50 stop pin 5' in the back part of the plug 30.

The blade holder strip 6 is secured slidably to the lower side of the frame extension plate 35 by means of guide blocks 36 fastened by screws 37. Stops 38 are fastened on strip 6 by screws 39 and serve to limit 55 the longitudinal movement of the blades in cutting and restoring.

Referring again to the stitch inserting mechanism 2, the post 10 carries the clamping device 12 and the needle holder 13. The 60 clamp 12 comprises a plunger rod 41 held by the guide members 42, 43 and 44 on post 10, a foot proper 45 at the lower end to bear upon the goods to be marked, an operating lever 46 and a lifting spring 47 to restore the plunger and lift the foot when the lever han-

dle 48 is released. Said lever is pivoted to arm 11 at 46'. A link 41' having a shoulder 41'' is pivoted to lever 46 at 46''.

The needle holding plunger 13 operates in guides 49 and 50. The lower end has a 70 socket to receive the shank of the needle 25 which is held by a set-screw 51. A restoring spring 52 raises the plunger 13 after each stitch. The needle may be driven down very forcibly through the goods 53 by reason of 75 the broad head 54 on the upper end of the plunger 13. The cylindrical plungers 13 and 41 are provided with lateral guide arms 55 and 56 respectively, both of which slide on the vertical guide rod 57, which is spaced 80 from said plungers in the casing of post 10.

In order to secure the lower end of the thread and prevent withdrawal while loops are being pulled a thread holding device is supplied on the underside of the bed plate 85 or frame 1. This attachment is in the form of a horizontally disposed pin 61, of pointed shuttle like shape, on the forward end of a plunger rod 62. Said rod is actuated by a lever 63 fulcrumed at 64 and connected to a plunger 65 which has a cam face 66 at its opposite end. The plunger 13 has a parallel branch 67 also provided with a cam face 68 to coact with face 66, so as to push rod 65 back when the needle descends. This advances rod 62 against the pressure of its restoring spring 69, and backs the shuttle stop pin 61 away from its effective position. Then when the needle 25 has reached its lowermost point and starts to ascend the pin 61 enters the loop 70 and holds the thread down. Said pin is carried by a bracket 71 on rod 62, as well shown in Fig. 7. The pin is held by screw 72.

In order to grip the thread in case only one strand is to be used the pin 61 is curved somewhat in a horizontal plane, as at 74 on Fig. 5, and is so positioned relative to a fixed block 75 that when the needle 25 is raised the pin 61 grips the thread tightly against said block and holds it while the marker loops are being pulled. A slight hook or notch 76 is provided on the underside of pin 61 near its point. The bend at 74 is exaggerated due to the small scale.

The operation and further details of the machine may be described as follows: Strips of material 53, as for instance cloth, are placed on the bed plate or platform 35 with the several blades 4 interposed as shown in Figs. 6, 7, 8, and 9, said blades all being swung fully back and retracted to their innermost positions as in Figs. 5 and 6, as provided for by swinging the arms 7 all counter-clockwise and pushing inwardly on the handle 8. In this position the needle 25 and bed perforation 78 are aligned with the inner ends of the blade slots 24. The foot 45 is next lowered and then the needle is operated. The handles 48 and 54 are

then both released and the blades 4 are operated successively beginning at the bottom. Then the foot 45 is again lowered and the handle 8 is pulled outwardly, thus cutting 5 the stitch markers apart. The foot is then raised and the goods are removed. The operation is then repeated with the next lay of goods.

Although but one specific embodiment of 10 this invention is herein shown and described it will be understood that some of the details of the construction shown may be altered or omitted without departing from the spirit of this invention as defined by the following claims.

It is to be understood that the lay or stack 20 of goods to be operated upon may be of any height or number of layers desired within the lift range of the needle and clamping foot above the bed plate. Although in some cases it is preferable to use double thread markers, it is more economical, and usually sufficient to use single thread stitches or markers. In the latter instance the peculiar 25 locking function of the block 75 is essential as will be apparent.

We claim:

1. A device for applying stitch markers comprising in combination a frame, a needle 30 and operating mechanism therefor arranged to carry a loop of thread through the lay, a catch operable crosswise of the tip of said needle to engage said loop and prevent withdrawal of the thread, and multi-bladed means to successively pull loops 35

in said thread between layers, each blade having an aperture to admit said needle and thread and each aperture being bordered by a sharp edge to cut said thread when said means are pulled lengthwise of 40 the blades.

2. In a device of the character described a loop puller comprising a series of blades to be interposed between the layers of goods and adjustable means to limit the pulling 45 movement of said blades.

3. In a device of the character described a loop puller comprising a series of blades to be interposed between the layers of goods, and manually operable handles of successively greater length to facilitate pulling serially and gang restoring means therefor. 50

4. In a device of the character described a loop puller comprising a series of blades to be interposed between the layers of goods, 55 and a handle for pulling said blades collectively lengthwise to cut the thread loops, said blades each having a sharp edge to engage the thread.

5. In a device of the character described 60 a loop puller comprising a series of blades to be interposed between the layers of goods, and means to move said blades lengthwise and stop means to limit their movement in each direction. 65

Signed at Chicago this 4 day of Aug., 1922.
